UNITED STATES PATENT OFFICE.

ISAAC SNOW, OF LAWRENCE, MASSACHUSETTS, ASSIGNOR TO DRAPER CORPORATION,
OF HOPEDALE, MASSACHUSETTS, A CORPORATION OF MAINE.

FEELER-MOTION FOR LOOMS.

1,369,483.

Specification of Letters Patent. Patented Feb. 22, 1921.

Application filed July 10, 1919, Serial No. 309,963. Renewed January 10, 1921. Serial No. 436,389.

To all whom it may concern:

Be it known that I, ISAAC SNOW, a citizen of the United States, residing at Lawrence, in the county of Essex and State of Massachusetts, have invented an Improvement in Feeler-Motions for Looms, of which the following description, in connection with the accompanying drawings, is a specification, like characters on the drawings representing like parts.

The present invention has reference to feeler mechanisms whereby when the filling in the active shuttle reaches a predetermined degree of exhaustion, a train of mechanism is set in operation to effect a change in the condition of the loom, such, for instance, as stopping the loom or changing the filling in the shuttle.

Various forms of feeler mechanisms have heretofore been provided, some of which feel for the filling in the shuttle and on substantial exhaustion thereof either stop the loom or effect replenishment of filling. Among these has been that type or class of feeler mechanisms wherein a feeler tip has been pivotally mounted upon a feeled carrier and turned upon its pivotal mounting by the frontward push of a surface within the shuttle when the filling has reached a predetermined degree of exhaustion to thereby effect replenishment of filling. The feeler motion of the present invention is of this type, and the object sought is to provide a feeler motion of the character described which shall be simple in construction, efficient and practical in its operation to cause replenishment of filling only when that in the active shuttle has become substantially exhausted.

The construction and mode of operation and effect of the feeler motion of the present invention will best be understood from the following description and accompanying drawings of one good practical form thereof, it being understood that variations in details may be made within the true scope of the invention which is defined by the claims.

In the drawings:—

Figure 1 is a perspective view of one side of the loom, showing sufficient parts thereof to indicate the associated relation of the feeler motion of the present invention with the coacting loom parts;

Fig. 2 is a plan view on an enlarged scale showing the position assumed by the parts

when, on a detecting beat, the shuttle contains a working supply of filling;

Fig. 3 is a view similar to that of Fig. 2 showing the relation assumed by the parts when on a detecting beat the filling is found by the feeler to be substantially exhausted; and

Fig. 4 is a detail enlarged view showing the connection of the auxiliary or slide member and the initiating arm.

65

The loom frame 1 has mounted thereon the brackets 2 which support the transverse or change shaft 3 usual to this type of loom. Secured to the transverse or change shaft 3 is an arm 4 extending upwardly therefrom and to which is pivoted at 5 the actuator 6, the rear end portion 7 of which is normally out of the path of movement of an operating member 8 which, in the present invention, may be the weft hammer or 75 a part connected thereto.

The lay 9 has the usual shuttle-box 10 provided in its front wall with an opening 11, and the shuttle 12 which carries the filling carrier or bobbin 13 has the adjacent wall 80 thereof at the side of the shuttle provided with an opening 14 as usual where a feeler is to feel through the front wall of the shuttle-box into the shuttle as the lay moves frontwardly on a detecting beat. The filling carrier or bobbin is also of usual type and may be held in the shuttle by the usual bobbin jaws, so that the entrance of the new filling carrier or bobbin with a supply of filling 90 thereon may cause the ejection of the old or depleted bobbin and the substitution therefor of the full or working filling supply bobbin.

The feeler, in the present invention, is mounted upon a feeler carrier normally held 95 in rearward position by yielding means, in order that the feeler tip shall enter the shuttle on each detecting beat and feel for or detect the condition of the filling in the shuttle. The feeler carrier may take various 100 forms, and the mounting of the feeler carrier may be variously contrived, but in the present instance of the invention, the loom frame has extending therefrom an arm 15 provided with a slot 16 by means of which 105 and a securing bolt 17 a bracket 18, adapted to support the feeler carrier may be adjustably held in desired position.

The feeler stand is of an appropriate character to support the feeler carrier, in the 110

present instance of the invention, and preferably consists of a sheet metal plate, portions of which are bent, as will hereinafter be described, to provide the necessary guideways and supporting elements for the parts of the feeler. The feeler stand 19 has the down-turned portions 20 between which is secured the block 21 (Fig. 1) through which securing bolts 22 may be passed to hold the 5 feeler stand in desired position of adjustment. In the present instance of the invention, the feeler carrier 23 is mounted for movement toward and from the front of the loom on the feeler stand, which latter is provided with suitable guideways or bearings 10 to direct the movement of the feeler carrier. As indicated in Fig. 1, the feeler stand 19 has its side edge portions 24 and 25 upwardly and inwardly turned to provide 15 guideways for the feeler carrier. This character of construction is simple and efficient and enables the feeler stand to be formed from a single plate of sheet metal.

The feeler carrier 23 has the two frontwardly extending guiding portions 26 and 27 which are connected by the bridge 28 and are guided in the bent guideways 24 and 25, the construction being such that the feeler carrier may be reciprocated and its movements directed by the guideways 24 and 25.

The feeler carrier is normally held in rearward position by means permitting it to yield frontwardly under the frontward pressure of the surface within the shuttle 30 on a detecting beat, and in the present instance of the invention, such means comprises a spring 29 surrounding a stem 30 secured to the bridge 28 of the feeler carrier, and having one end resting against the front 35 of the bridge as indicated, and the other end resting against a lug 31 upturned from the feeler stand and through which the stem 30 projects. The stem 30 is provided with an angular end portion 32 which by engagement with the lug 31 limits the rearward movement of the feeler carrier.

The feeler tip 33 has a primary fulcrum connection with the feeler carrier at 34 and is provided with an engaging end portion 50 35 which may be toothed or roughened as shown, with the line of teeth or roughened engaging end portion extending in a direction obliquely or angularly to the longitudinal axis of the shuttle when the filling tip is 55 in position as indicated in Figs. 1 and 2.

Connected to the feeler tip 33 between its primary fulcrum connection 34 with the feeler carrier and toothed or roughened engaging end portion 35 is the auxiliary member or slide 36 having the auxiliary fulcrum connection with the tip at 37 and extending frontwardly therefrom. The auxiliary member or slide 36 extends through the bridge 28 of the feeler carrier and frontwardly 65 thereof is engaged by an arm, which for

identification may be herein known as the initiating arm.

The initiating arm 38, in the present instance of the invention, is pivotally mounted for movement with the feeler carrier and 70 preferably secured to the feeler carrier bridge 28 by a pivotal connection 39. The initiating arm 38 has a downturned portion 40 (Fig. 4) provided with an open slot 41 adapted to engage a groove 42 in the front 75 end portion of the auxiliary member or slide 36, the construction being such that should the auxiliary member or slide 36 be given a frontward movement independent of the feeler carrier or relative thereto, the initiating arm 38 will be moved about its pivotal mounting 80 39 on the bridge of the feeler carrier.

The initiating member 38 has a side projecting portion 43 which is pivotally connected to a transmitter 44 as indicated in Fig. 1, the other end of the transmitter 44 being connected to one arm 45 of the bell-crank lever 46 pivotally mounted on a stand 47 rising from the loom frame. The other 90 arm 48 of the bell-crank lever 46 underlies the actuator 6, the construction being such that should the initiating arm 38 be turned upon its pivotal connection by the carrier 23 by independent frontward movement of 95 the auxiliary member or slide 36, the transmitter will be moved endwise to the right in the illustrated form of the invention in Fig. 1, thereby lifting the arm 48 of the bell-crank 46 and moving the end of the actuator 100 6 into the path of movement of the operating member 8, thus causing actuation of the train of mechanism for replenishment of filling.

When a working supply of filling is present in the shuttle on a detecting beat, the obliquely arranged toothed portion 35 of the feeler tip will engage the mass of filling and sink into it, so that on further frontward movement of the lay the feeler carrier 23 and 105 the parts connected thereto including the initiating member will be moved frontwardly without disturbing the relation between the carrier, the auxiliary member or slide 36 and the initiating member. When, 110 however, the filling is substantially exhausted on a detecting beat as indicated in Fig. 3, the tooth engaging end portion of the feeler tip will engage the few turns of filling still remaining on the bobbin within 115 the shuttle, or the surface of the bobbin itself, and upon further frontward movement of the lay, the feeler tip will be turned upon its primary fulcrum 34 relative to the feeler carrier into the position indicated in Fig. 3. 120 During this turning movement the teeth on the engaging end of the feeler tip will assume a practically parallel relation with the axis of the shuttle, and in case there is still sufficient filling in the shuttle for weaving 125 130

- purposes, the feeler tip will be held from turning sufficiently from its position in Fig. 2, as the additional teeth engage the filling, and replenishment will not be effected.
- 5 Should, however, the feeler tip complete its movement about its primary fulcrum connection 34 with the feeler carrier 23 from the position of Fig. 2 to that of Fig. 3, the auxiliary member 36 will be moved front- 70 wardly against the tension of its spring 49 which is interposed between a collar 50 and the bridge 28 and cause the initiating member 38 to be swung about its pivotal connection 39 with the feeler carrier, the feeler 75 carrier itself remaining in its rearward position. The swinging movement of the initiating member will be transmitted through the transmitter 44 and cause the actuator 6 to be moved into operative relation 20 with the operating member 8 and effect actuation of the train of mechanism for replenishment of filling.
- What is claimed is:—
1. In a feeler motion for looms, the combination of a feeler stand, a feeler carrier having side portions guided for reciprocating movement in the feeler stand, a bridge extending between the side portions of the feeler carrier, a feeler tip having a primary 90 fulcrum connection with the feeler carrier, an auxiliary slide member having an auxiliary fulcrum connection with the feeler tip intermediate its primary fulcrum and engaging end and passing frontward of the bridge, an initiating member pivotally mounted on the feeler carrier bridge and engaging the auxiliary slide member, a transmitter connected to the pivoted initiating member, and means controlled by the transmitter for replenishing filling.
  2. In a feeler motion for looms, the combination of a feeler stand, a feeler carrier having side portions guided for reciprocating movement in the feeler stand, a bridge 95 extending between the side portions of the feeler carrier, a feeler tip having a primary fulcrum connection with the feeler carrier, an auxiliary slide member having an auxiliary fulcrum connection with the feeler tip intermediate its primary fulcrum and engaging end and passing frontward of the bridge, a spring acting through the auxiliary slide member between the bridge and feeler tip, an initiating member pivotally mounted on the 100 feeler carrier bridge and engaging the auxiliary slide member, a transmitter connected to the pivoted initiating member, and means controlled by the transmitter for replenishing filling.
  3. In a feeler motion for looms, the combination of a feeler stand, a feeler carrier having side portions guided for reciprocating movement in the feeler stand, a bridge 105 extending between the side portions of the feeler carrier, a feeler tip having a primary fulcrum connection with the feeler carrier, an auxiliary slide member having an auxiliary fulcrum connection with the feeler tip intermediate its primary fulcrum and engaging end and passing frontward of the bridge, an initiating member pivotally mounted on the feeler carrier bridge and engaging the auxiliary slide member, a transmitter connected to the pivoted initiating member, and means controlled by the transmitter for replenishing filling.
  4. In a feeler motion for looms, the combination of a feeler stand, a feeler carrier movable toward and from the front of the loom, a feeler tip having a primary fulcrum connection with the carrier and provided with teeth arranged oblique to the longitudinal axis of the shuttle when the feeler is in feeling position, an auxiliary member fulcrumed to the feeler tip between its primary fulcrum and end teeth, 80 an initiating member movable with and relative to the feeler carrier, a connection between the auxiliary member and initiating member to impart relative movement between the feeler carrier and auxiliary member when 90 the auxiliary member is moved by turning movement of the feeler tip under the frontward pressure when the filling is substantially exhausted.
  5. In a feeler motion for looms, the combination of a feeler stand, a feeler carrier mounted in the feeler stand for reciprocating movement, a feeler tip having a primary fulcrum connection with the feeler carrier and a toothed engaging end, an auxiliary sliding 100 member fulcrumed to the feeler tip at one side of the primary fulcrum, an initiating member pivotally connected to the feeler carrier and engaging the auxiliary sliding member, and means for causing replenishment of 105 filling when the auxiliary sliding member is moved frontwardly by the feeler tip as it is turned about its primary fulcrum by the frontward pressure when the filling is substantially exhausted.
  6. A feeler motion for looms, comprising, in combination, a movable feeler carrier, a laterally movable feeler tip provided with a primary fulcrum connection with the carrier and having a toothed or roughened engaging end, an auxiliary member pivotally connected to the feeler tip at one side of the primary fulcrum and adapted to be displaced frontwardly by turning movement of the feeler tip about its primary fulcrum connection with the feeler carrier, and means actuated by frontward movement of the auxiliary member to cause filling replenishment when the filling is substantially exhausted.
  7. A feeler motion for looms, comprising, 125 in combination, a movable feeler carrier, a laterally movable feeler tip provided with a primary fulcrum connection with the carrier, and having a toothed engaging end in which the line of teeth are at an angle to the 130

longitudinal axis of the shuttle when the feeler is in normal rearward position, an auxiliary member connected to the feeler tip between the primary fulcrum and engaging end of the feeler tip and displaced forwardly by turning movement of the feeler tip about its primary fulcrum connection with the feeler carrier, and means moved laterally by the forward movement of the auxiliary member forwardly when the filling is substantially exhausted for causing replenishment of filling.

8. A feeler mechanism for looms, comprising, in combination, a feeler carrier movable toward and from the front of the loom, a

feeler tip having a primary fulcrum connection with the feeler carrier and a part extending laterally from the primary fulcrum, an auxiliary member or rod pivotally connected to the lateral extension of the feeler tip at 20 one side of the primary fulcrum, a spring normally acting through the auxiliary member or rod to maintain the feeler tip in feeling position, and means for effecting replenishment of filling when the feeler tip is 25 moved laterally on a detecting beat with filling substantially exhausted.

In testimony whereof, I have signed my name to this specification.

ISAAC SNOW.
